Inventor
CYRIL A. BOUCHER

GW Earushard Attorney

UNITED STATES PATENT OFFICE.

CYRIL A. BOUCHER, OF JOPLIN, MISSOURI.

ATTACHMENT FOR CIGAR-BUNCHING MACHINES.

Application filed July 8, 1921. Serial No. 483,123.

To all whom it may concern:

Be it known that I, CYRIL A. BOUCHER, a citizen of the United States, residing at Joplin, in the county of Jasper and State of Missouri, have invented certain new and useful Improvements in Attachments for Cigar-Bunching Machines, of which the following is a specification.

This invention relates to a binder holder or attachment for cigar bunching machines, the purpose of which is to hold a leaf of tobacco in position that a portion of it may be rolled about the filler under slight tension and automatically torn off as the bunching operation progresses and is completed.

Heretofore the practice has been to cut or tear the leaf of tobacco into pieces of approximately the required size and shape for use as binders, by hand process, prior to spreading a section loosely on the apron of the bunching machine; but this practice has been found to be slow, inefficient and wasteful as much of the valuable binder leaf has been discarded. In the present invention an attachment comprising two levers, one of which is mounted on the table or bed plate of the bunching machine, the other of which is pivotally mounted and adapted to be brought into engagement with the rigidly mounted lever by the operation of the bunching machine. The binder leaf having been placed between said levers it is automatically held in position and torn off as rolled on the bunch, using only the exact and proper amount of the binder leaf that is required to cover and hold the bunch in form. The objects attained are a saving in labor and utilizing the entire binder leaf.

A further object is to provide a mechanism that will stretch the binder leaf by uniform tension and prevent it from folding or doubling while being rolled about the filler thereby producing a smooth and more desirable bunch.

In the accompanying drawings, I have shown one embodiment of the invention. In this showing:

Figure 1 is a side elevation of a bunching machine showing the invention applied, and showing a bunching machine in operation,

Figure 2 is a similar view showing the position of the parts at the beginning of an operation,

Figure 3 is a detail perspective view of the attachment,

Figure 4 is a rear elevation of the machine showing the invention applied,

Figure 5 is a front elevation, and,

Figure 6 is a detail sectional view on line 6-6 of Figure 1.

In this illustration, I have shown the attachment applied to one standard type of bunching machine, but it is to be understood that the use of the invention is not restricted to this single machine as it may be employed with various types of bunching machines.

The machine to which the attachment is connected comprises a base 1 mounted on a table 2 or other suitable support. A pair of spaced standards 3 form the supports for the bunching mechanism. A bed plate or table 4 is secured to the base in any suitable manner, and projects forwardly. A trough 5 is formed at the front of the bed plate. A transverse shaft 6 is mounted in suitable bearings formed in the upper ends of the standards and this shaft carries a pair of arms or levers 7 connected to each other at their lower ends by means of a roller 8. A suitable handle 9 is arranged between the two levers to permit hand operation. An apron 10 is secured to the front of the bed plate and extends rearwardly from the bed plate, as shown. When the machine is in operative position, a trough 11 is formed in the apron. The apron passes upwardly over the roller 8, as shown in Figure 2 of the drawings, and is secured to a roller 12, carried by a pair of arms 13. These arms are provided with projecting members 14 on their upper ends adapted to be received in cam tracks 15 of a cam 16. Each of the cams are further provided with slots 17 adapted to receive pins 18, carried by the lever 7. The cams are pivoted to the standards 3, at 19.

The attachment forming the subject matter of the present invention comprises a support or base plate 20, adapted to be secured to the base of the bunching machine. As shown, the plate is provided with flanges 21, having openings 22 for the reception of suitable fastening means, the base plate being arranged transversely of the bunching machine. A pair of ears 23 are formed on the plate, the ears forming bearings for the reception of a shaft 24. An upright member 25 is provided with an opening for the reception of the shaft to permit lateral adjustment of the member. The bottom of the upright member is provided with a foot 26.

26, engaging the base plate. A rod or lever 27 is secured in an opening adjacent the upper end of the upright member, the rod being threaded, as at 28, and adapted to receive a nut 29. This rod is arranged over the bed plate of the machine, as shown in Figures 1 and 2 of the drawings, and is provided with a hooked end 30, adapted to engage the front of the bed plate. A pair of spaced rods 31 are adapted to cooperate with the rod 27 to hold the binder. As shown in Figure 6, the spaced rods, when in lowered position, are arranged on each side of the rod 27, and the tobacco leaf 32 forming the binder is clamped between the rods. The spaced rods are pivotally mounted on a shaft 24, being provided with U-shaped portions 33 having openings for the reception of the shaft. A spring 34 is secured to the rear ends of the pivoted levers to normally retain them in the position shown in Figure 2 of the drawings. The roll 8 is provided with a reduced end 35, adapted to engage the rods 31 when the bunching machine is operated.

As the bunching machine is of the usual construction, a detail description of the operation is deemed unnecessary. When the bunching operation is to be performed, the filler is placed in the trough 11 and the handle 9 grasped by the operator and moved forward. The binder is placed on the portion of the apron overlying the bed plate with its rear edge projecting into the trough 11. Heretofore, the binder leaf has been cut to the proper size before being placed in the machine, but by the use of the present invention, the binder leaf is torn at the side of the machine, thereby eliminating the necessity of preparing the binder leaf in the proper size. The movement of the pins 18 in the slots 17 of the cams turns the cams on their pivots and moves the arms 13 rearwardly from the position shown in Figure 2 of the drawings, to the position shown in Figure 1 of the drawings, drawing the apron 10 rearwardly and bunching the filler. During the first half of the operation, the cam action rolls the bunch firmly and then slowly relaxes, allowing the last half to roll smoothly but not tight.

The operation of the attachment is as follows:

As the pivoted levers 7 are moved forward, the roller 8 engages the pivoted rods 31 moving them on their pivots against the action of spring 34 to the position shown in Figure 6 of the drawings. As the bunch is rolled by the apron, the leaf is rolled around it and carried forwardly. The leaf being clamped by rods 27 and 31 is prevented from moving and the portion of the leaf surrounding the bunch is thus severed to form a binder. The forward movement

of the apron carries that portion of the leaf 65 overlying the apron forwardly and severs it from the remainder of the leaf clamped between the bars 27 and 31. The rods 31 and the rod 27 are slightly spaced thereby gripping the leaf instead of cutting it. This 70 gripping action stretches the leaf from the rod 27, causing it to tear adjacent the inner side of the inner arm 31. It has been found that the tearing operation is advantageous, as it stretches the binder and tears at the 75 proper place without waste.

By means of the lateral adjustment of the rods 27 and 31, the attachment may be fitted to various types or sizes of bunching machines. When the attachment is put in 80 place, the nut 29 is tightened and the engagement of the hook 30 with the bed plate retains the rod 27 in position. The pull exerted on the upright member 25 by the rod 27 maintains the foot 26 in engagement 85 with the base plate and prevents lateral movement. When the nut 29 is loosened, the upright member 25 may be laterally adjusted.

It is to be understood that the form of my invention herewith shown and described is to be taken as a preferred example of the same, and that various changes in the shape, size, and arrangement of parts may be resorted to without departing from the spirit 95 of the invention or the scope of the subjoined claims.

Having thus described my invention, I claim:

1. An attachment for cigar bunching machines comprising a fixed rod arranged on the bed plate of the machine, and a pivoted spaced rod arranged adjacent said fixed rod and adapted to be swung on its pivot by the operation of the bunching mechanism to hold the binder firmly that it may be torn the desired length as the bunching operation progresses.

2. A bunching machine comprising an apron, a pair of pivoted levers, a roller connecting said levers, said apron passing over said roller, a bed plate, means operable by the movement of said levers to bunch a filler arranged on said apron, a fixed rod arranged on said bed plate, and a pivoted spaced rod cooperating therewith to firmly hold the residue of the binder leaf when the bunching mechanism is oscillated to tear therefrom the portion required for the bunch.

3. A bunching machine comprising a bed plate, an apron arranged over said bed plate, a pair of pivoted levers, a roller connecting said levers, said roller being arranged under said apron to bunch a filler when the levers are moved on their pivots, a fixed rod mounted on the bed plate, and a pivoted rod arranged over said bed plate and operated

by said roller to firmly hold the binder that it may be torn adjacent to said rod.

4. A bunching machine comprising a bed plate, an apron arranged over said bed plate, a pair of pivoted levers, a roller arranged between said levers, said apron passing over said roller, a fixed rod mounted on said bed plate, a pivoted rod arranged over said bed plate and adapted to cooperate with said fixed rod to firmly hold the binder, and a spring for normally maintaining said pivoted rod in raised position.

5. A device for firmly holding cigar binders during the bunching operation comprising a rod arranged on the bed plate of a bunching machine, and a pivoted spaced rod arranged over said bed plate and cooperating with said first mentioned rod to securely hold the binder as it is being stretched

around the filler and torn off adjacent the 20 inner edge of said spaced rod.

6. A device for securely holding cigar binders during the bunching operation comprising a rod arranged on the bed plate of a bunching machine, a pivoted spaced rod 25 arranged over said bed plate and cooperating with said first mentioned rod to firmly hold the binder residue while the portion required to cover the filler is being torn therefrom by the operation of the bunching machine, and means for normally maintaining said spaced rod in a raised position.

In testimony whereof I affix my signature in presence of two witnesses.

CYRIL A. BOUCHER.
